X-RAY CONTROL CABINET

William F. Bruning, Greenwich, Conn., assignor to Picker
X-Ray Corporation, Waite Mfg. Div. Inc., Cleveland,
Ohio, a corporation of Ohio

Application February 25, 1954, Serial No. 29,217

Term of patent 14 years

(Cl. D26—5)

The single figure is a front perspective view of an X-ray control cabinet, showing my new design.

The dominant feature of my design resides in the portions shown in full lines.

I claim:

The ornamental design for an X-ray control cabinet, substantially as shown and described.
